UNITED STATES PATENT OFFICE.

FRANKLIN K. HICKOK AND ROBERT M. LAMBIE, OF NEW YORK, N. Y.

COMBINED CARRIAGE-JACK, WRENCH, AND BIT-STOCK.

SPECIFICATION forming part of Letters Patent No. 397,499, dated February 12, 1889.

Application filed April 5, 1888. Serial No. 269,889. (No model.)

To all whom it may concern:

Be it known that we, FRANKLIN K. HICKOK and ROBERT M. LAMBIE, citizens of the United States of America, and residents of New York, in the county of New York, State of New York, have invented certain new and useful Improvements in a Combined Carriage - Jack, Wrench, and Bit-Stock, of which the following is a full, clear, and exact specification thereof.

Our invention relates to a combined lifting-jack, adjustable wrench, and bit-stock, all of which will be fully described hereinafter.

Our invention consists of a goose-neck or bow composed of any suitable material—preferably of malleable iron—one end of said goose-neck being provided with a fulcrumed axle-bearing, the opposite end provided with an adjustable wrench, and the whole provided with means whereby the entire device may be used as a bit-stock.

In the drawings, Figure 1 represents a side elevation of the device, showing the main features of our invention. Fig. 2 is an enlarged sectional view taken on line X X. Fig. 3 is an enlarged front view of the adjustable wrench and bit-stock. Fig. 4 is an enlarged plan view of the portion above the jaws of the wrench where the operating-screw is permanently held. Fig. 5 is an enlarged plan view of the end of the fulcrumed axle-bearing.

Similar letters refer to similar parts throughout the drawings, in which—
a represents the bow or goose-neck having the axle-bearing *b* fulcrumed to one end thereof. The forward end of the goose-neck is provided with a fixed jaw and bearing portion, *c*, in which bears the operating-screw *d*, permanently held by the collar *e*. This screw *d* passes through and engages with corresponding threads made in the adjustable jaw *f*, provided with ears *g*, adapted to operate over the bead *h* of the goose-neck. The central portion of the goose-neck is provided with a cylindrical portion, *i*, which of course serves as a handle in addition to the handle *k*, when using the device as a wrench or bit-stock.

The end of the fulcrumed axle-bearing *b* is concaved and a portion of the concavity is provided with corrugations or serrations *n*, adapted to catch onto the threads of the axle

of a vehicle when sliding the wheel thereof onto the fulcrumed axle-bearing *b*.

It will be observed that the collar *e*, before the screw *d* is inserted, will have the appearance of a yoke, as indicated by dotted lines 55 in Fig. 4. The operating-screw *d* is first inserted into the adjustable jaw *f*, and the lower end of the said screw is inserted in a depression made in the fixed jaw *c*, and the jaw *f* is then pushed into the space *l* 60 until the ears *g* thereof shall have reached a point directly opposite the beads *h*, when it is then slid down upon said beads *h*. In the meantime the shoulder *p* of the screw *d* will have assumed a position beneath the collar 65 *e*, after which the ears *m* are bent around the shank of the said screw *d* and the shoulder *p* thereof, holding it permanently in position.

The axle-bearing *b* (represented in full lines, Fig. 1) is ready to be placed against the 70 end of an axle, at which time the wheel is slipped thereon; but when using the device as a wrench or bit-stock the fulcrumed axle-bearing is thrown up, as indicated by dotted lines in Fig. 1, thus giving the power-arm full 75 play.

Modus operandi.—The nut of the vehicle-axle is first removed by the wrench portion of the device, which will have such a firm grip on the nut as to prevent its dropping. 80 The journal or wrench end (still holding the nut) is passed between the wheel-spokes, the bearing portion of the fixed jaw resting upon the axle of the vehicle, and the corrugated end of the fulcrumed axle rests against the thread 85 thereof. The goose-neck is then raised until the wheel shall have left its tangential bearing, when it is then removed over to the fulcrumed axle-bearing *b*, and there performs the function of a prop while the vehicle-axle is being greased.

Having thus described our invention, what we claim as new, and desire to secure by Letters Patent, is—

The herein-described compound tool, comprising the bow or goose-neck *a*, the axle-bearing *b*, fulcrumed to one end thereof and having serrations *n* at its forward end, the fixed jaw and bearing portion *c*, arranged at the forward end of the said goose-neck *a*, the 95 100

screw *d*, permanently held by the collar *e*, the
adjustable jaw *f*, provided with ears *g*, the
latter engaging with the beads *h*, the cylin-
drical portion *i* of the said goose-neck, and
5 the handle *K*, substantially as shown and de-
scribed.

In testimony that we claim the foregoing

we have hereunto set our hands this 3d day
of April, 1888.

FRANKLIN K. HICKOK.
ROBERT M. LAMBIE.

Witnesses:

CHAS. E. FOULDS,
J. A. HURDLE.
